UNITED STATES PATENT OFFICE.

ULYSSES G. MCJUNKIN, OF IGNACIO, COLORADO.

NAIL HOLDER AND CARRIER.

1,139,879.

Specification of Letters Patent. Patented May 18, 1915.

Application filed November 24, 1913. Serial No. 802,827.

To all whom it may concern:

Be it known that I, ULYSSES G. MCJUNKIN, a citizen of the United States, residing at Ignacio, in the county of La Plata and State of Colorado, have invented new and useful Improvements in Nail Holders and Carriers, of which the following is a specification.

The invention relates to an improvement in nail holders and carriers comprehending a structure in which nails can be housed in bulk and arranged by gravity to project the nail in part beyond the receptacle for convenient grasping by the operator.

The main object of the present invention is the provision of a nail holder and carrier including a rotatable receptacle in which the nails are stored in bulk, the receptacle being formed to provide slotted openings through which nails are in part projected by gravity to form such projecting portion to be grasped by the operator for the removal of the nail from the receptacle for driving.

The invention in its preferred form of details will be described in the following specification, reference being had particularly to the accompanying drawings, in which:

Figure 1 is a perspective view of the improved holder and carrier. Fig. 2 is a vertical section of the same. Fig. 3 is a plan of one of the sides of the receptacle illustrating particularly means for adjusting the nail slots.

Referring particularly to the accompanying drawings, the improved nail holder and carrier comprises a base 1 preferably of board like element having edge strap members 2 for the reception of straps for supporting article from the shoulders and strap members 3 for the reception of the straps to be passed about the waste or body whereby the receptacle can be carried by the workman in a readily accessible position without inconvenience and without requiring use of either hand for the purpose.

Secured to the base 1 are outstanding frame members 4 of V-shape terminating at an appropriate distance from the base in bearing disks 5. Mounted between the frame members 4 is a holder or receptacle 6, preferably of approximately square outline with end walls 7 provided with trunnions 8 for rotative mounting in the bearing disks 5 of the frames 4 whereby the holder

is mounted for free rotary movement between said frame members.

Two of the opposing side walls as 9 and 10 are fixed with relation to the end walls 7 and one of said side walls as 9 is formed with an opening 11 adapted to be covered by a plate 12 pivotally connected to the wall at 14 and having any desired form of catch 13, the opening 11 serving as a means for introducing the nails into the holder.

The respective side walls are spaced apart throughout the width of the holder at the respective meeting ends of said side walls, providing slots 15 opening throughout the full width of the holder and adapted to be temporarily closed at respective ends by spring strips 16 secured to the end walls 7 with their free ends closing the ends of the slots. To provide for adjustment of the width of the slots to accommodate nails of different sizes the remaining side walls 17 and 18 of the holder are adjustable, being duplicates in construction. Each of said walls 17 and 18 is made up of two sections 19 and 20 having the full width of the box but an aggregate length less than the similar dimension of the box. Plates 21 project from the end walls 7 and overlie the sections 19 and 20, screws 22 passing through the plates and into plates or bars 20' underlying the sections, screws passing between the edges of the sections so that the plates 20' and 21 act as clamps to maintain the sections in adjusted relation. By appropriately adjusting the sections of the respective walls 17 and 18 it is obvious that nail slots 15 may be given any desired width within the limits and thereby accommodate nails of different sizes.

The trunnion 8 adjacent one end wall 7 is provided with a fixed washer or similar member 23 having a periphery made up of a series of angularly related edges 24, the leaf spring 25 secured upon the adjacent frame 4 being designed to cooperate with the edges 24 to maintain the holder temporarily in any desired position.

In use a suitable quantity of nails are placed in the holder through the opening 11 and certain of said nails will find their way through the lowermost slot 15 and be held so projected by the heads of the nails. The holder is now given limited turn by the operator so as to free said projected nails from the wedge of mass of nails within the

holder without causing the projected nails to return to position within the holder. The nails thus projected can be readily grasped and removed from the slot by lateral pressure against the spring member 16. With the holder in proper position, the nails may be removed from one end of the slot in which they are in position for driving upwardly without turning them from the other 10 end of the slot when they will be in position for driving downwardly without turning.

The improved device is admirably adapted for carrying in a conveniently accessible position a number of nails and delivering at each 15 movement of the receptacle a number of such nails to the position from which they may be conveniently and readily removed.

Copies of this patent may be obtained for five cents each, by addressing the "Commissioner of Patents, Washington, D. C."

by the operator singly and in a direction which will permit the application of such 20 nails for driving with a change of movement of the hand.

What is claimed is:—

A rotatable nail holder of box like form having relatively fixed end walls and two 25 opposing side walls, the remaining side walls being formed of sections adjustable with relation to each other to space the meeting edges of the side walls to provide slots.

In testimony whereof I affix my signature 30 in presence of two witnesses.

ULYSSES G. McJUNKIN.
